UNITED STATES PATENT OFFICE.

KARL R. SCHUSTER, OF NEW YORK, N. Y., ASSIGNOR TO FRANCIS M. BARTON, OF CHICAGO, ILLINOIS.

CONCRETE BUILDING.

1,217,645.

Specification of Letters Patent. Patented Feb. 27, 1917.

Application filed February 9, 1911. Serial No. 607,620.

To all whom it may concern:

Be it known that I, KARL R. SCHUSTER, a citizen of the United States, and a resident of the city of New York, borough of Manhattan, county and State of New York, have invented new and useful Improvements in Concrete Buildings, of which the following is a full, clear, and exact description.

This invention relates to certain improvements in concrete building, and more particularly to the reinforcement of the concrete slab flooring, whereby the strains and stresses occurring within the flooring adjacent to the columns or other supports will be better taken care of.

In my improved construction, I provide a main reinforcement distributed uniformly over the floor space, irrespective of the presence of columns or other supports for the floor, and over these columns I provide a separate or auxiliary reinforcement, which has its main portion disposed adjacent to the upper surface of the floor, and presents downwardly extending portions distributed around the support to constitute shear members. This auxiliary reinforcement may assume various different forms, but it preferably comprises a series of rods properly positioned and having the outer ends of the rods forming the shear members.

Reference is to be had to the accompanying drawings which form a part of this specification, and in which similar reference characters indicate corresponding parts in the several views.

Figure 1 is a plan view of a portion of a floor, showing the reinforcement in position, ready for the concrete, and showing one form of auxiliary reinforcement which I may employ over a column;

Fig. 2 is a vertical section through the complete floor, said section being taken on a line corresponding to the line 2—2 of Fig. 1;

Fig. 3 is a plan view of another form of auxiliary reinforcement;

Fig. 4 is a vertical section somewhat similar to Fig. 2, but showing the reinforcement of Fig. 3, the main reinforcement not being illustrated;

Figs. 5 and 6 are views similar to Figs. 3 and 4, but showing a further form of auxiliary reinforcement.

Figs. 7 and 8 are views similar to Figs. 4 and 2, but showing another arrangement of rods to form the auxiliary reinforcement;

Figs. 9 and 10 are views similar to Figs. 3 and 4, but showing a further modified form;

Figs. 11 and 12 are similar views of a still further form of auxiliary reinforcement;

Figs. 13 and 14 are views similar to Figs. 7 and 8, but showing another arrangement of auxiliary reinforcement; and

Figs. 15 and 16 are plan views of other auxiliary reinforcements which may be employed.

As a main reinforcement I employ two sets of reinforcing rods or bars, the rods or bars of one set being parallel to each other and at right angles to the rods or bars of the other set.

In Fig. 1, I have illustrated rods 20 going to make up one set and rods 21 going to make up the other set, all of these rods being disposed substantially at a 45° angle to the walls 22 and 23 of the building. These walls are preferably of concrete, and may have piers 24 formed integral therewith. The two sets of rods 20 and 21 are disposed in uniform spaced relationship over the floor and subdivide the latter into a large number of rectangular spaces. The rods which pass over the columns are preferably heavier than the others.

To reduce the weight of the floor and to avoid the use of such a large quantity of concrete, I may place in each of these separate spaces or compartments a whole tile or block of terra-cotta. The specific construction of these hollow tiles or blocks do not embody any portion of the invention herein claimed and, therefore, they have not been illustrated in detail.

In the upper left-hand portion of Fig. 1, I have illustrated diagrammatically a few of these blocks or tiles, to show their respective positions in respect to the reinforcement. Preferably these blocks or tiles are of the character illustrated in my prior application No. 554,982, filed April 12, 1910.

It is not at all essential that the rods 20 and 21 extend at an acute angle to the walls of the building as is shown in Fig. 1. The two sets may be arranged parallel to the two right-angular walls, if desired. In Figs. 7 and 13, I have illustrated two sets of rods 27 and 28 at right angles to each other, the rods 27 being parallel to one wall 22 of the building and the rods 28 being parallel to the wall 23.

For supporting the floor intermediate be-

tween the walls, I utilize concrete columns of any suitable form and reinforced in any suitable manner. In the accompanying drawings, I have illustrated concrete columns 29, without illustrating any type of reinforcement. It is, of course, understood that some kind would preferably be employed.

- My invention relates particularly to the 10 reinforcement of the floor at those places directly above the columns and in the immediate vicinity of the columns. This reinforcement, which is separate from the main reinforcement of the floor, is what I 15 designate an auxiliary or secondary reinforcement, and, which in combination with the columns and the main reinforcement, constitutes the main feature of my invention. This auxiliary or secondary reinforcement 20 may be constructed in numerous different ways, but it is preferably formed of rods either fastened together or placed in position separately. These rods are preferably deformed so as to form a better bond with 25 the concrete, and each rod has a portion disposed adjacent to and substantially parallel with the upper surface of the floor, and a portion extending toward the lower surface of the floor to constitute a shear member. 30 I do not wish to be limited to any specific arrangement of rods in this auxiliary or secondary reinforcement, inasmuch as the same general effect may be secured in different ways. In Figs. 1 and 2, I have illustrated 35 an auxiliary reinforcement over the column 29 and formed of two sets of rods 30 and 31. All of the rods 30 are parallel to each other and parallel to the main rods 20, and all of the rods 31 are also parallel 40 to each other and are at right angles to the rods 30, in other words, parallel to the rods 21. This network of rods 30 and 31 covers that portion of the floor directly above the column 29, and also covers a considerable 45 area of the floor surrounding this portion over the column. Each of the rods 30 and 31 has its center portion disposed closely adjacent to the upper surface of the floor and its end portions bent downwardly and outwardly so as to terminate adjacent to the lower surface of the floor. This downwardly extending portion lies substantially 50 parallel to the direction of shearing stresses, and constitutes shear members. 55 In Figs. 3 and 4, I have illustrated a form of auxiliary reinforcement in which rods 32 are arranged radially rather than in separate parallel sets, and in which each rod extends from the periphery of the reinforced area inward radially and terminates just beyond the center of the auxiliary reinforcement. Each of these rods 32 has its outer end bent downwardly to form a shear member, and each rod adjacent to the center 60 of the reinforcement extends across and is 65

supported by a ring 33. At its inner end, each rod extends down through this ring so as to form a secure anchorage directly over the column. I have not illustrated the main reinforcement in Fig. 4, although it is, of course, understood that such a main reinforcement would be employed.

In the forms of auxiliary reinforcement illustrated in Figs. 1 to 4 inclusive, the rods are not rigidly connected together before being placed in position, unless it be by means of suitable wires wrapped around the contacting portions. Such wires have not been illustrated, as they would tend to confuse rather than elucidate the important 70 features.

In Figs. 5 and 6, I have illustrated a form which is preferable in many respects and which has all of the rods forming the auxiliary reinforcement rigidly connected together. In this form, I provide a loop 34 formed of metal of any suitable character, and through this loop all of the rods 35 extend. After all of the rods have been assembled within the loop and with the loop 90 at the center of each rod, suitable wedges 36 and 37 are driven into the loop to bind the rods in place and to subdivide them into two groups. The outer ends of the rods are then bent laterally so as to distribute 95 them in radial and spaced relationship, as illustrated in Fig. 5. These rods 35 have their ends bent downwardly to form shear members.

This reinforcement may be shipped in separate pieces and assembled on the job, or the rods may be rigidly secured within the loop or ring 34 and have their end portions spread apart after the reinforcement arrives at the job.

In Figs. 7 and 8, I have illustrated the type of reinforcement somewhat similar to that shown in Figs. 3 and 4, but in which the rods 37 are bent to form hooks 38 engaging with the ring 33 instead of merely passing through the ring to form an anchorage as in forms shown in Figs. 3 and 4. These rods are arranged radially, and their hooked engagement with the ring resists any tendency toward longitudinal movement under the stress to which they are subjected.

The rods may have radial arrangement without the employment of any ring. In Figs. 9 and 10, I have illustrated a form on which there are two sets of rods 39 and 40, one set being superposed on the other at the center and the outer portions of the rods bent laterally in respect to the superposed portions so as to give the proper radial distribution. A further form in which the rods may be arranged radially without necessitating the employment of a ring is shown in Figs. 11 and 12. In these figures there is one set of rods 41 having parallel center portions and diverging ends similar 120 125 130

to the rods 40, and, in addition to this, there is a second set of rods 42, each of which has a hook portion engaging with and receiving the parallel center portions of the rods of the other set.

The hook portions of the rods 42 serve to hold the rods of the other set together, and also serve as anchors for their respective rods.

16 In Figs. 13 and 14, I have illustrated a form of auxiliary reinforcement somewhat similar to that shown in Figs. 1 and 2, except that instead of employing single-spaced rods, I bend each rod to form an elongated 15 loop with parallel side portions 42 and 43, which are substantially the equivalent of two adjacent rods of the form shown in Figs. 1 and 2. The loop has its ends bent downwardly to form two parallel shear members 20 connected together at their lower ends, and this connection may be utilized for the auxiliary reinforcement to the main or primary reinforcement of the floor. As shown, the horizontal rods 28 of the main reinforcement 25 extend through one set of bends and the rods 27 extend through the other set. Thus, the entire reinforcement is woven or connected together to prevent displacement during the admission of the concrete.

30 As previously stated, Figs. 9 and 11 show different radial arrangements of the rods without the employment of a connecting ring or loop. Fig. 15 shows a further arrangement in which a central pin 44 is employed, around which rods 45 forming one set are bent in one direction and rods 46 forming a second set are bent in the opposite direction. These two sets of rods may lie in superposed planes, and although they are not exactly 40 radial, they are approximately so far as the strain exerted is concerned. The central pin 44 may, if desired, be omitted, in which case the rods could be looped together as shown in Fig. 16. In this arrangement, the rods 45 are divided into two sets 47 and 48, and each rod is bent at the center to a greater or less degree by interlocking the center loops, each set of loops being anchored to the other set.

45 It is not thought necessary to show side elevations or sections of the reinforcement shown in Figs. 15 and 16, as it is understood that each of these rods preferably has its outer end bent downwardly to form a shear member.

50 The auxiliary or secondary reinforcement is employed to take care of the negative bending moment in the floor slab, for which purpose said reinforcement is positioned over or in vertical alinement with the post or column, and near the top surface of the floor slab, whereas the positive bending moment is taken care of in the floor slab by the main reinforcement which is shown as the two series of crossing rods positioned in the floor slab near the underside thereof. Im-

portant features of my auxiliary reinforcement are, first, that the rods composing it have their respective end portions extended downwardly from the horizontal plane of the body portion of the reinforcement itself, which downwardly extended portions of the rods intersect with the plane of the rods composing the main reinforcement, so that the downwardly extended portions of the rods composing the auxiliary reinforcement 70 constitute shear members for the slab where the latter joins with the capital of the column; second, the auxiliary reinforcement is separate and distinct from the metal reinforcement of the floor slab and from the 75 reinforcement of the column when the latter reinforcement is employed, and, third, in a preferred form of the invention the auxiliary reinforcement is in the form of a metal mat composed of two series of rods the ends 80 of which are looped and are extended downwardly from the plane of the body of the mat, the rods of one series crossing or intersecting with the rods of the other series 85 so as to produce the mat.

90 The employment of a mat separate from, and independent of, the floor slab reinforcement and the column reinforcement is an advantage for the reason, mainly, that the rods are bent and assembled to produce the 95 mat at a factory or other manufacturing establishment, at which place, the mat can be, and is, made by the employment of unskilled labor, whereas to assemble the rods at the time of installing the floor slab requires the 100 use of skilled and more expensive labor. In addition, the complete mat is more easily and rapidly installed, thus saving time and labor, when the workmen are engaged in installing the floor slab. It is apparent that 105 with the mat in a complete, ready to be laid condition, it can be placed over the column, and the rods of the main reinforcement are then interlaced with the downwardly inclined looped end portions of the rods composing the mat constituting the auxiliary reinforcement, after which the concrete material is dumped or deposited and tamped 110 into place, the several rods being so disposed as to allow ample space for thoroughly 115 tamping the concrete.

Having thus described my invention what I claim as new and desire by Letters Patent, is:

1. In a concrete building the combination 120 with a floor slab and supporting column therefor of main reinforcing rods for the floor slab and an auxiliary reinforcement incorporated in the floor and disposed over the column, said auxiliary reinforcement being formed of two sets of intersecting rods, the end portions of these latter being inclined downwardly to cross or intersect the horizontal plane of the main reinforcing rods and said downwardly inclined portions 125 130

of the auxiliary rods being bent back so as to form loops through which the main reinforcing rods extend.

2. In a concrete building, the combination with a floor slab, a supporting column therefor, and main reinforcing rods to take care of the positive bending moment of said slab, of an auxiliary reinforcement embedded in the floor slab near the top surface thereof and positioned in substantially the vertical plane of said supporting column for taking care of the negative bending moment of said floor slab, said auxiliary reinforcement being separate from said main reinforcing rods and being composed of rods the end portions of which are extended downwardly from the horizontal plane of the body of said auxiliary reinforcement, said downwardly extended end portions of the rods composing said auxiliary reinforcement having loops which receive the main rods and said downwardly extending end portions constituting shear members for the floor slab supporting column.
3. In a concrete building, the combination with a floor slab, a supporting column therefor, and main reinforcing rods to take care of the positive bending moment of said slab, of an auxiliary reinforcement embedded in the floor slab near the top surface thereof and positioned substantially in the vertical plane of said supporting column for taking care of the negative bending moment of said floor slab, said auxiliary reinforcement being separate from said main reinforcing rods and comprising rods each of which has a portion thereof disposed horizontally in the same plane as all the other rods and the end portions of which rods are inclined downwardly from the horizontal plane of the body forming said horizontal portions of the rods composing said auxiliary reinforcement, said downwardly inclined portions of the auxiliary rods being locked with the main reinforcing rods and constituting shear members for the floor slab capital of said supporting column.

4. In a concrete building, the combination with a floor slab, a supporting column therefor, and main reinforcing rods embedded in the floor slab near the under surface thereof for taking care of the positive bending moment, of an auxiliary reinforcement embedded in the floor slab near the top surface thereof and positioned in vertical alinement with the column and the capital thereof for taking care of the negative bending moment of said slab, said auxiliary reinforcement consisting of rods separate and disconnected from the main reinforcing rods, said auxiliary rods each having a certain part thereof horizontally disposed over the column and the end portions of said auxiliary rods being inclined downwardly from the horizontal plane of the body of said auxiliary

reinforcement formed by the horizontal portions of said rods, said downwardly inclined end portions of the auxiliary rods having locking engagement with said main reinforcing rods and constituting shear members for the floor slab of the supporting column.

5. In a concrete building, the combination with a floor slab, a supporting column therefor, and main reinforcing rods embedded in said slab near the under surface thereof, of auxiliary reinforcing rods embedded horizontally in said slab near the upper surface thereof and positioned over the supporting column, said auxiliary rods having their end portions extended downwardly from the plane of the horizontal portions thereof and said downwardly extended rods crossing the horizontal plane of the main reinforcing rods so as to serve as shear members for the floor slab where it joins with the column, said downwardly extended ends of the auxiliary rods being looped and said main rods extending through the loops of said extended ends of the auxiliary rods.

6. In a concrete building, the combination with a floor slab, a supporting column therefor, and main reinforcing rods embedded in said slab near the under surface thereof, of an auxiliary reinforcement composed of two series of crossing rods constituting a mat separate from the main reinforcing rods, said mat being embedded in the floor slab near the upper surface thereof and positioned in vertical alinement with said column, said rods composing the auxiliary reinforcement mat having their respective end portions inclined downwardly from that horizontal plane of the body forming said mat and said downwardly inclined ends of the rods being looped, the main reinforcing rods extending through the loops of the auxiliary rods and the downwardly inclined ends of the auxiliary rods constituting shear members for the floor slab adjacent to the column.

7. Building construction embodying supporting columns, a floor slab, main reinforcing rods positioned in the lower part of the floor slab, and an auxiliary reinforcement positioned over the column and in the upper part of said slab, said auxiliary reinforcement embodying substantially horizontal rods provided at their ends with loops extended downwardly to meet said main rods, said main rods engaging or interlacing with said loops.

8. A unitary metal mat or grille for reinforced floor slabs composed of two series of crossing rods the ends of which rods are provided with loops, said loops being inclined relatively to the plane of the body of said mat formed by said crossing rods said inclined loops of the mat or grille being adapted for the reception of other rods which co-

BEST AVAILABLE COP

1,217,645

operate to reinforce a floor slab in the area between slab-supporting columns.

9. A metal mat or grille for reinforced floor slabs comprising connected horizontally positioned rods forming the body of said mat or grille, the end portions of said rods being formed into loops and said loops being inclined relatively to the plane of said body, said inclined loops of the mat or grille being adapted for the reception of other rods which coöperate to reinforce a floor slab in the area between slab-supporting columns.

10. Building construction embodying a flat slab supported on columns extending in rows, main rods incased in the slab at the lower part thereof, said main rods comprising two series with the rods of one series crossing the rods of the other series in the area between the columns, and an auxiliary reinforcing mat positioned in the slab near the top surface thereof and in vertical alinement with the column, said auxiliary reinforcing mat being separate from the main rods and comprising short rods having their end portions extended downwardly from the plane of the mat and locking with the main rods and serving as shear members for said slab.

11. Building construction embodying a flat slab supported on columns extending in two directions, main reinforcing rods incased within the slab adjacent to the lower surface thereof, said main rods comprising two series of rods arranged for the rods of one series to cross the rods of the other series in the area between the columns, and auxiliary reinforcements positioned in the slab adjacent to the upper surface thereof and in the vertical plane of said columns, each auxiliary reinforcement comprising a unitary structure composed of attached rods the end portions of which are extended downwardly through the material of the slab, which extended end portions of said attached rods are locked with the main rods and perform the function of shear members for said slab.

12. Building construction embodying a flat slab supported on columns extending in two directions, main reinforcing rods positioned within the slab adjacent to the under surface thereof, said main rods being in two series with the rods of one series crossing the rods of the other series in the area be-

tween the columns, and auxiliary metal reinforcements positioned within the slab near the top surface thereof and in vertical alinement with the respective columns, each auxiliary reinforcement being composed of rods united in a unitary structure separate from the main rods and adapted to be positioned as a unit within the material of the slab, said rods of the unitary auxiliary reinforcement being provided with downwardly inclined end portions extending through the material of the slab and having locking engagement with the main rods and serving the function of shear members for said slab.

13. A mat member for a column head reinforcement in a flat slab floor construction, formed of a series of rods arranged in substantially parallel relation and in substantially a common plane and having their outer ends connected together, said rods at their ends being extended downwardly to the lower portion of the slab.

14. A mat for a column head reinforcement in a flat slab floor construction, comprising members, each of which is formed of a series of rods arranged in substantially parallel relation and in substantially a common plane and having their outer ends connected together, the rods of one member crossing and overlying the end of the other member, said members at their ends being extended downwardly to the lower portion of the slab.

15. A reinforced concrete structure comprising columns, a flat slab floor, and mats formed of belts of rods disposed substantially parallel to and near the top of the slab and extending longitudinally and transversely and resisting the bending moment over the columns, and extending outwardly from the column beyond the point of counter-flexure, and belts of rods close and parallel to the bottom of the slab and extending between the columns and resisting the positive bending moment, said mats having loops in which the bottom rods are laid.

In testimony whereof I have signed my name to this specification in the presence of two subscribing witnesses.
